UNITED STATES PATENT OFFICE.

FREDERICK G. SARGENT, OF WESTFORD, MASSACHUSETTS, ASSIGNOR TO C. G. SARGENT'S SONS CORPORATION, OF WESTFORD, MASSACHUSETTS, A CORPORATION OF MASSACHUSETTS.

DRIER.

No. 873,796.

Specification of Letters Patent.

Patented Dec. 17, 1907.

Application filed May 22, 1907. Serial No. 375,123.

To all whom it may concern:

Be it known that I, FREDERICK G. SARGENT, a citizen of the United States, residing at Westford, in the county of Middlesex and 5 State of Massachusetts, have invented a new and useful Drier, of which the following is a specification.

This invention relates to machines for drying wool, cotton and other similar substances 10 and more especially to that type of driers in which a screen is located in a drying chamber for supporting the material to be dried.

In my Patent No. 675,070 granted May 28, 1901, I have shown a drier of this kind in 15 which the air is circulated through a longitudinal chamber and through the material on the screen. This device was provided with a side conduit or by-pass through which the air not passing through the screen could be 20 brought around from the upper part of the chamber to the lower part below the screen but the opening through which the air was obliged to pass had to be protected by a screen to prevent the fibrous material from 25 passing through with the draft and being lost. This screen was apt to get clogged up on account of the fibers brought into contact with it.

One of the objects of this invention is to 30 provide a construction in which the advantages of the above machine may be obtained without the disadvantage of the frequent clogging of the screen leading to the by-pass.

Other objects of the invention are to provide 35 means whereby the screen may readily be removed and cleaned if necessary; to provide means for regulating the flow of air through the conduit; to provide means for deflecting the air in the drying chamber in 40 several ways so as to insure better circulation and provide more surely for its passage through the screen and material to be dried, this being accomplished by means of partitions so located as to secure these results; 45 also to provide improved means for controlling the passage of the air from the fan or circulating devices; that is, to permit them to discharge the air from the machine or circulate it therein; and generally to improve 50 and simplify the construction of machines of this type.

Reference is to be had to the accompanying drawings which illustrate preferred forms of the invention as applied to a certain 55 type of drying machine and in which,

Figure 1 is a plan of such a machine. Fig. 2 is a sectional view of the same on the line 2—3 of Fig. 1, looking toward the left-hand side of the sheet. Fig. 3 is a sectional view on the same line looking in the opposite direction. Fig. 4 is a sectional view on the line 4—4 of Fig. 1. Fig. 5 is a sectional view on the line 5—5 of Fig. 1, and Fig. 6 is a view similar to Fig. 3 showing another way in which the invention can be carried out in 60 65 this type of machine.

The invention is illustrated as applied to that kind of drier in which the casing 10 has an endless conveyer 11 therein in the form of a screen passing over two drums 12 which 70 supports the wool or other material to be dried on the upper strand thereof. In this type of drier, the fibrous material is fed to the conveyer by a feed apron 13. In the side of the casing at one end is an air inlet 14, which is usually open, but which can be closed by a door or damper 142. In the chamber 15 at one side are a series of air circulating devices 16 preferably in the form of fans driven in any desired way and shown in 75 80 the present instance as drawing air down through the upper strand of the screen 11. There are preferably a plurality of these circulating devices located at the two ends of the machine. In the form shown in the first 85 five figures, there are four of them, while in the form shown in Fig. 6, there are only two. The drying chamber and the heating chamber 15 are separated by a partition 28 which has openings 29 in front of the fans and extends a short distance above the screen or 90 apron 11.

By reference to Fig. 4, it will be seen that when the air circulating devices are constructed so as to draw the air in the manner 95 indicated by the arrows, the air will pass upwardly through the chamber 15 and pass among heating pipes 17 or the like over the partition 28 into the top of the drying chamber and down through the upper strand of 100 the screen back to the space between the two strands of the screen, but it passes through the drier toward the next fan so that it takes approximately a spiral course through the 105 drying chamber. This is the circulation which ordinarily takes place from one end of the machine to the other when it is operated in the usual way. The chamber 15, however, is provided with an outlet 18 near the end opposite the inlet. The outlet has a 110

regulating door or damper 19. When this is in the position shown in Fig. 4 the air instead of continuing to circulate in the manner described above will be forced out through the outlet or if the fan works in the other direction the air will be drawn in at this point.

The parts so far described with the exception of the outlet from the chamber may be constructed in the same manner as the corresponding parts shown in my above mentioned prior patent. In that patent is shown a conduit or by-pass opening from the upper part of the drying chamber to permit air to pass over the same into the bottom of the drying chamber. This is to take care of the air not passing through the material to be dried. On account of the disadvantages of the particular construction of that by-pass which have been set forth above, I have provided in this case an opening 20 in the top of the drying chamber and with this I have connected a directly upwardly extending conduit 21 which is connected through a conduit 22 with an opening 23 to discharge air into the drying chamber below the strand of the screen which holds the material to be dried. By means of the horizontal opening in the top of the chamber and the upwardly extending conduit therefrom, it will be seen that the fibers of the material will not so readily cling to the screen 24 with which the opening is provided and, consequently, one of the disadvantages of the former construction is overcome. Moreover, this screen is mounted in horizontal ways 25 so that it may be withdrawn by means of a handle grip or extension 26 so that it may be cleaned if any lint or fibers are deposited upon it. In the conduit 22 is also located a swing damper 27 which may be turned to any desired position so as to vary the amount of air passing through the conduit and shut it off if desired.

In addition to the features already described, this invention comprises another feature of advantage in that the circulation of the air is improved and controlled by means of a series of partitions 30, 31 and 32 located respectively above the top strand 50 between the two strands and below the bottom strand of the endless screen. The partition 30 extends downwardly from the top of the drying chamber nearly to the upper strand of the screen so that the material passing along under it will prevent air from passing over it. Consequently, the air coming to this partition in either direction must pass downwardly through the screen and thus have more efficiency to dry the material thereon. This partition is also preferably located at one side of the opening 20 so that air before entering said opening must pass through the screen when it comes from one end of the chamber.

The partition 31 is located between the two

strands as stated and being offset from the partition 30 a substantial distance so that the partitions are separated by a space through which air may circulate, it serves a function similar to that of the partition 30. That is, the air passing along the drying chamber below the screen, said air having once passed through the screen or through the conduit 22, is forced to pass upwardly again through the steam coils 17 and then down through the material on the screen to further assist in drying it. The space immediately above the partition 31 over the screen is free so that the air may pass along the screen above the partition.

The partition 32 is mounted on hinges or pivots so that it may be kept in vertical or horizontal position. Being located directly below the partition 31 when it is in vertical position it forces the air coming against this partition in one direction to pass upwardly through the coils as has been stated and when turned to a horizontal position it permits said air to pass below the partition 31 and consequently if too much air is passing upwardly this can be regulated by turning this partition 32 to a horizontal position. A damper or door 33 is also located in the top of the partition 31 for a similar purpose.

It will be observed that the partitions 30 and 31 are off-set from each other so as to permit the air to pass between them either downwardly or upwardly through the material to be dried. They are preferably located near the opposite ends of the opening 20 so that the air toward this opening may be forced downwardly as has been stated and the air passing along the lower part of the drying chamber from either end of the same may be forced upwardly through the coils 10 and out this opening if it is adjusted to permit the same.

I have described the device as having only one inlet and outlet but I prefer to have an additional inlet 140 and outlet 180 so that when both are open more air can be forced through the device and it will not travel so far before being discharged. In ordinary use, however, the outlet 180 and inlet 140 will be closed by doors or dampers 190 and 141 respectively. The device can be operated also with the fans at one end only operating which causes a straight draft through one end and the above described spiral one through the other.

The form of the invention shown in Fig. 6 is substantially the same and is designed for a similar type of machine. As the parts are of similar character, they will not be described in detail.

While I have illustrated and described two forms in which I prefer to embody the invention, I am aware that many changes may be made therein by any person skilled in the art without departing from the scope of the in-

vention as expressed in the claims. Therefore, I do not wish to be limited to the particular forms shown, but

What I do claim is:—

5. 1. In a drier, the combination of a drying chamber, a screen therein for supporting a layer of material to be dried, means for causing air to circulate through said drying chamber to pass through the stock on the 10 screen, and an outlet opening upwardly from the top of said chamber at one side and extending downwardly and entering the chamber below the screen, whereby the air which does not pass through the stock may 15 be caused to flow back under the screen.

2. In a drier, the combination of a drying chamber, a screen therein for supporting a layer of material to be dried, means for causing air to circulate through said drying chamber to pass through the stock on the 20 screen, an outlet opening upwardly from the top of said chamber at one side and extending downwardly and entering the chamber below the screen, whereby the air which does 25 not pass through the stock may be caused to flow back under the screen, and a screen in the opening in the top of the chamber for preventing fibrous material from passing into said outlet.

30. 3. In a drier, the combination of a drying chamber, a screen therein for supporting a layer of material to be dried, means for causing air to circulate through said drying chamber to pass through the stock on the screen, 35 an outlet opening directly upwardly from the top of said chamber and extending downwardly and entering the chamber below the screen, whereby the air which does not pass through the stock may be caused to flow 40 back under the screen, and a removable horizontal screen extending across said outlet and the opening in the top of the chamber.

4. In a drier, the combination of a drying chamber, a screen therein for supporting a 45 layer of material to be dried, means for causing air to circulate down through the screen, an upwardly opening outlet in the top of the chamber at one side opposite said circulating means, a conduit from said outlet opening 50 into the chamber below the screen and on the same side of the chamber, a substantially horizontal screen over said opening horizontal guides for said horizontal screen, and a damper in said outlet for controlling 55 the amount of air passing therethrough.

5. In a drier, the combination of a chamber, a plurality of circulating devices arranged adjacent thereto for drawing air through the chamber, a screen longitudinally located in the chamber for supporting material to be dried, an outlet in the top of one side of the chamber near the center thereof, a conduit opening directly upwardly from said outlet and connected with 60 the chamber below the screen, and a down-

wardly extending partition in the chamber adjacent to one end of said outlet to deflect the currents of air downwardly through the screen and secure a better circulation.

6. In a drier, the combination of a chamber having a plurality of air circulating devices near one side thereof, a longitudinal screen for supporting material to be dried, a by-pass or conduit opening from above the screen and discharging at a point below the 75 screen, and a partition depending from the top of the chamber to a point near the screen, said partition being located near one end of said conduit or by-pass.

7. In a drier, the combination of a chamber having a plurality of air circulating devices near one side thereof, a longitudinal screen for supporting material to be dried, a by-pass or conduit opening from above the screen and discharging at a point below the 80 screen, a partition depending from the top of the chamber to a point near the screen, said partition being located near one end of said conduit or by-pass, and a second partition located below the screen and adjacent to the 85 other end of said conduit or by-pass, both of said partitions being located between said air 90 circulating devices.

8. In a drier, the combination of a chamber, a longitudinal screen therein for supporting material to be dried, a plurality of air circulating devices located on opposite sides of the center of the chamber, a partition depending from the top of the chamber and extending substantially to the screen, and a partition 95 below the screen and extending therefrom downwardly, said partitions being offset from each other a substantial distance, 100 whereby a current of air will be forced through the screen between the partitions. 105

9. In a drier, the combination of a chamber, a longitudinal screen therein for supporting material to be dried, a plurality of air circulating devices located on opposite sides of the center of the chamber, a partition depending from the top of the chamber and extending substantially to the screen, and a partition 110 below the screen and extending therefrom downwardly, said partitions being offset from each other a substantial distance, 115 whereby a current of air will be forced through the screen between the partitions.

10. In a drier, the combination of a chamber, a screen therein for supporting material to be dried, a plurality of air circulating devices, and a partition extending downwardly from the screen to deflect the air circulating in the chamber and causing it to pass through the screen, the space over the screen immediately above said partition being free, whereby 120 the air may pass along the screen above the partition.

11. In a drier, the combination of a chamber having an endless screen therein for supporting material to be dried on its upper sur- 125

face, a partition depending from the top of the drying chamber substantially to the top of the upper strand of the screen, and a partition between the two strands of the screen, 5 said partitions being separated by a space through which the air may circulate from one side thereof to the other.

12. In a drier, the combination with a drying chamber of an endless screen therein, a 10 partition above the upper strand of the screen, a partition between the strands of the screen off-set from the other partition, and a movable partition below the lower strand and below the partition which is located between 15 said strands.

13. In a drier, the combination with a drying chamber, of a screen therein for supporting stock to be dried, a stationary partition below the screen and a movable partition be- 20 low the stationary partition.

14. A drier having a drying chamber hav- 25 ing an inlet at one end, a second inlet on the same side and near the center, an outlet at the opposite end and on the opposite side and

a second outlet on the same side as the first 25 outlet but located near the center of the chamber.

15. A drier having a drying chamber having an inlet at one end, a second inlet on the same side and near the center, an outlet at 30 the opposite end and on the opposite side, and means for closing the inlet near the center.

16. In a drier, the combination of a drying chamber, and air circulating devices at one 35 side thereof, an outlet or inlet located adjacent to said air circulating devices, and a swing door adapted to be moved to two different positions whereby the air may be forced out of or into the chamber or may be caused to circulate within the chamber. 40

In testimony whereof I have hereunto set my hand, in the presence of two subscribing witnesses.

FREDERICK G. SARGENT.
